RETRACTABLE DOG LEASH

Manfred Bogdahn, Drogensee 30a,
2000 Hamburg 266, Germany

Filed Oct. 25, 1973, Ser. No. 409,720

Claims priority, application Germany Sept. 26, 1973

Term of patent 7 years

Int. Cl. D30—04

U.S. Cl. D30—39

FIG. 1 is a perspective view of a retractable dog leash showing my new design in a reeled-in position;

FIG. 2 is a top plan view thereof in a reeled-out position; and

FIG. 3 is a side elevational view shown in a reeled-in position.

I claim:

The ornamental design for a retractable dog leash, as shown and described.
